COMPOSITE ELECTRODE

Archibald F. Meston, Bound Brook, N. J., assignor
to Research Corporation, New York, N. Y., a
corporation of New York

Application May 3, 1941, Serial No. 391,789

4 Claims. (Cl. 183—7)

This invention relates to a system of electrodes useful in establishing an electric field or electric fields across a gas-filled space for the purpose of ionizing the gas and electrically transporting particles suspended in the gas. It relates in particular to a composite electrode comprising one or more attenuated elements from which corona discharge can be made to emanate and an adjacent element of extended surface upon which a strong non-discharging electric field can be made to terminate.

In the following description and exposition, the term "collecting electrode" will be used to designate those electrodes which in common electrical precipitation practice provide surfaces for the reception or collection of particles which have been driven from the air stream by an electric field, and upon which a portion, at least, of the electric field terminates. The complementary electrode, usually called a discharge electrode, will be referred to as a "composite electrode" or "precipitating electrode" from time to time herein and will be understood to comprise a non-discharging element, or elements, which is designed to serve as one terminal of the strong electric field that is established to bring about the migration of any charged particles suspended in air which may flow through the electric field, and a discharge or ionizing element which is comprised of one or more members having surfaces of very small radii of curvature and from which discharges capable of ionizing adjacent gases are caused to emanate.

A principal object of the invention is to provide electric treating means whereby a composite discharge electrode energized at one potential when opposed by a suitable complementary electrode of the so-called "collecting" type energized at another potential effects the formation of a charging field, comprising an ionizing discharge, and a transporting or precipitating field, without discharge, in closely adjacent zones.

This and other objects and advantages are obtained by the provision of a composite electrode comprising an extended surface portion free from surface elements of radius of curvature small enough to produce corona discharge under operating conditions and a discharge surface portion of very small radius of curvature supported by the extended surface portion, the discharge surface portion projecting from the extended surface to a distance not exceeding the smallest radius of curvature of the extended surface portion adjacent the discharge surface portion and having an aggregate length at least a multiple of such projection distance, said composite electrode being symmetrically positioned between parallel spaced extended surface collecting electrodes defining a gas treating space therebetween and in-

cluding opposed portions projecting into the gas treating space to provide a constricted zone in said space, at least one of the portions of the composite electrode being positioned in the constricted zone provided by the projecting portions of the collecting electrode.

While the character of surface which will produce corona discharge will vary with such conditions as potential difference, electrode space and character of the gas, the extended surface member of the discharge electrode should not, in general, include surface portions having a radius of curvature substantially less than one-tenth inch while the attenuated discharge members will include surface portions having radii of curvature of the order of five-thousandths of an inch or less.

The invention will be more particularly described with reference to the accompanying drawing in which:

Fig. 1 is a diagrammatic sectional elevation of an electrical treater embodying the principles of the invention;

Fig. 2 is a partial section on line 2—2 of Fig. 1; Fig. 3 is a diagrammatic representation in longitudinal section of a modified form of electrical treater embodying the principles of the invention;

Fig. 4 is an enlarged fragmentary view of the lower end of the composite electrode of Fig. 1;

Fig. 5 is an enlarged end view of the same electrode;

Figs. 6, 7 and 8 are representations of modified forms of electrodes embodying the principles of the invention;

Fig. 9 is a sectional view of the electrode of Fig. 8 on line 9—9 of Fig. 8;

The treater diagrammatically shown in Figs. 1 and 2 comprises a casing for the flow of gases, including flat plates 10 providing collecting electrode surfaces, a top or cover plate 11, and a bottom plate 12. In the construction of Figs. 1 and 2 means is provided for varying the relative field strengths adjacent the precipitating and the discharging elements of the discharge electrode, by varying the position of the discharge electrode with respect to portions 10a of the collecting electrode members, which portions project into the interelectrode space. In the position of the discharge electrode 19, shown in full lines, the difference between the strengths of the electric fields adjacent the two portions of the electrode is substantially greater than in the position shown in dotted lines. In a construction embodying this principle, the discharge electrode may be adjustably positioned in the treater for movement back and forth to adjust for varying conditions of treatment.

The composite discharge electrode 19 com-

prises precipitating member 20, typically a smooth, rigid rod or tube of circular, elliptical, ovate or suitably shaped section, and discharge members 21, 22 consisting of, in the embodiment shown, prongs of very fine wire. The discharge electrode is suspended in the known manner from insulated support 23. The collecting electrodes are grounded at 24 and the discharge electrode is connected at 25 to an energizing system in the manner well known in the art of electrical precipitation.

The construction shown in Fig. 3 is a modified embodiment of the construction of Figs. 1 and 2 which permits a very strong precipitating field to be realized under conditions which make for continuity of operation.

Auxiliary electrode members 10b are smooth, round rods or tubes, which function as collecting electrode elements. They are caused to rotate continuously against cleaning means 24 which prevent the building up of deposits of material which might cause "back-corona." As in the construction of Figs. 1 and 2, the relative strengths of the precipitating field and the ionizing field may be varied by adjusting the position of the discharge electrode 19 with respect to elements 10b.

When a voltage difference of say 10 to 30 kilovolts per inch is impressed across the space between electrodes 19 and 10, a strong electric field exists in that space which is strongest where the so-called lines of force are the shortest and most concentrated and most nearly parallel.

The conditions realized by energization of the arrangement just described can be summarized as follows:

An electric field is established which is most intense, on the average over its entire length, between electrode surfaces from which no corona discharge emanates. This portion of the electric field is designated as a precipitating field. Portions of the electrical field of appreciably less average intensity terminate on attenuated portions of that electrode known as the discharge electrode and cause local corona discharges therefrom. This portion or portions of the field is designated as the ionizing field though it may function to some extent as a precipitating field.

The average strengths of the precipitating and ionizing fields will vary with the distance of the non-ionizing and ionizing portions, respectively, of the discharge electrode from the collecting electrodes. The relative values of precipitating and ionizing fields can thus be made to vary by changing the shape and dimensions of the electrodes, particularly of the discharge electrode.

The flatter and smoother the non-ionizing surfaces of the complementary electrodes the closer they can be positioned at a given voltage difference without disruptive discharge and the stronger the resulting electric field.

The more attenuated and isolated the discharge elements, the more intense will be the discharge from them, conditions of voltage and electrode spacing remaining constant.

When the discharge elements are positioned in close proximity to a portion of the non-discharging surface, but at a considerably greater distance from the collecting electrode than certain other portions of the non-discharging surface, the discharge elements will be masked or shadowed by the close-by non-discharging surface and a very high voltage drop across the electrodes will be required if the electric field at the

discharge elements is to become intense enough to cause corona discharge. Under these conditions, the precipitating field will have become very strong and effective for migrating charged particles when the ionizing field is still relatively weak and comprises low energy discharges only. Such conditions are especially desirable when air is to be cleaned for human consumption. The intensity of the discharges and the resulting yield of ozone can be controlled while the precipitating field is maintained at as near maximum strength as is practical.

Also, if the discharge elements are of very small radii of curvature and are spaced some distance apart, the electric field as it leaves such an element expands to fill the space just beyond it and in a very short distance has become so weak that the phenomena which are responsible for chemical changes in the air—the formation of ozone and of oxides of nitrogen, as examples, are not sustained. It is believed that such changes are limited to a very short period within the discharge itself, when use is made of the present invention.

Electrodes for providing the above results can be of simple design and inexpensive. As an illustration, electrode 19 of Figs. 1 and 2 of the accompanying drawing, as shown more particularly in Figs. 4 and 5, may advantageously be made of two half round bars, with a radius of one-half inch which are joined together with solder to form a round member 20, and prongs 21, 22 of .005" diameter tungsten wire, one end of each prong being inserted between the half rounds (with flat sides solder coated) before the half rounds are sweated together. All surfaces are made smooth, the end of bar 20 is rounded if it is not joined to other members, and any joints are left free from cracks or other openings. The prongs will vary in length and number, depending upon the voltage and spacing to be maintained between the electrodes and the degree of ionization desired in the gases undergoing treatment. Good results have been obtained, for example, when the discharge electrode comprised a bar one inch in diameter and prongs of .005 inch diameter wire, one-eighth inch long, spaced one-quarter inch apart along the bar. This was placed in the center of a treating passage for air defined by parallel flat plates spaced six inches apart. The flat plates functioned as collecting electrodes and were maintained at ground potential. The discharge electrode was connected to the negative terminal of a source of unidirectional current with a peak voltage above ground of about 65 k. v. The prongs pointed in the opposite direction to the air flow which was at about five feet per second.

For high velocity air flow and high efficiency of dust removal, several electrodes, such as the one just described, are preferably placed in series in the air passage.

In the discharge electrode of Figs. 4 and 5, means is shown to prevent undesirable discharge off the rounded end of member 20. Rounding the end of member 20 does relieve the concentrated fields that exist when that member has a squared end or a pointed end, but, even so, it has been found that at very high voltages a single rough spot, or a small lump of foreign matter of particular composition, or a crack in the surface there will become the focus of a locally strong field and cause a discharge of unwanted character. The discharge from such a spot is inclined

to be of reddish color and extends well out from the surface of the electrode. The amount of ozone formed by such discharge is considerably greater than that formed by the discharge leaving one of the prongs. The objectionable discharges may be eliminated by providing prongs 22 at the bottom, similar to prongs 21 positioned on the side, of member 20. The intensity of the discharge from each prong can be governed by the length and number of prongs used and by the position of the prongs with relation to the collecting electrodes.

A valuable characteristic of the discharge obtained with electrode 19 is the so-called electric wind it produces. This electric wind, causing air that would otherwise be motionless to move in the interelectrode space in a resultant direction parallel to the collecting electrodes, has been measured and has been found to have an average velocity in excess of three feet per second. Actually, the wind comprises local currents that tend to follow the electric field as represented by lines of force and, as electric lines of force tend to repel one another, the result is a fan-like movement of the ions and charged particles inducing movement of the air generally out from the prongs and over to the collecting electrodes. Of course, air must enter the region about the prongs if it is to be aspirated out of that region, so something of a vortical movement of the air results. This movement of air caused by the electric wind is imposed on the normal movement of the air as it is blown through the interelectrode space, say, by a fan producing an induced draught. With the electric wind opposing the normal flow of air through the precipitator—a result obtained by having the discharge prongs point toward the inlet of the precipitator, a very general and thorough mixing of the ions produced by the discharges and the passing air is obtained with the desired result that all the suspended solid and liquid particles in the air are electrically charged and are caused to migrate in the electric field. The precipitating fields, previously discussed, which extend from the flat portions of the composite electrode to the collecting electrodes are relatively free from electric wind and are particularly adapted for removing the charged particles from the air stream.

As indicated above, the preferred embodiment of the invention includes prongs or just points, rather than edges or wires, as discharging elements. A prong projecting out from a surface can be of the terminal of lines of force extending in every direction except back along the prong. This means that an electric field which is relatively weak a short distance from the prong will be strong enough at the prong itself to cause an ionizing discharge. The closer together the prongs are placed, the weaker will the field at each prong become, or, putting it another way, the more intense the adjacent field must be to cause corona to emanate from the points. When the prongs touch one another the condition presented by an edge is obtained. A wire, parallel to the supporting member, as indicated at 21a in Fig. 6, can be used as a discharge element in the present invention. From the standpoint of providing ionizing discharges adjacent weak electric fields it is to be considered intermediate in this respect between an edge and spaced points.

Fig. 7 shows a composite electrode with prongs 21b extending out front and back, a construction

sometimes useful under particular circumstances as when a greater degree of ionization of the gases is desired.

The composite electrode, of Figs. 8 and 9, provides a wire discharge element 21c spaced from extended surface element 20c by means of fingers 23, to which the wire is soldered.

With an apparatus of the form and dimensions described, effective precipitation of suspended particles from air, with no spark-over and little or no production of ozone, can be obtained with a voltage of 30 to 35 k. v. (root mean square), maintained across the electrodes by connecting the precipitating electrode to a source of rectified high potential alternating current, such as the transformer and rotary mechanical switch arrangement, commonly used in electrical precipitation circuits and grounding the collecting electrode.

20 I claim:

1. In an electrical precipitator, substantially parallel spaced extended surface collecting electrodes defining a gas treating space therebetween, and including opposed portions projecting into 25 the gas treating space to provide a constricted zone in said space, and an elongated discharge electrode symmetrically positioned between said collecting electrodes, extending transversely of the gas stream and comprising an extended surface member free from surface portions of radius of curvature small enough to produce corona discharge under operating conditions and a plurality of attenuated discharge members carried by said extended surface member presenting surface portions of very small radius of curvature substantially confined to a single plane parallel to the collecting electrodes, at least one of said members being positioned in the constricted zone provided by the projecting portions of the collecting electrode.

2. In an electrical precipitator, substantially parallel spaced extended surface collecting electrodes defining a gas treating space therebetween, and including opposed portions projecting into 45 the gas treating space to provide a constricted zone in said space extending transversely of the gas stream, and an elongated discharge electrode symmetrically positioned between said collecting electrodes, extending transversely of the gas stream and comprising an extended surface member free from surface portions of radius of curvature small enough to produce corona discharge under operating conditions and a plurality of attenuated discharge members carried by said 50 extended surface member presenting surface portions of very small radius of curvature substantially confined to a single plane parallel to the collecting electrodes, at least one of said members being positioned in the constricted zone provided by the projecting portions of the collecting electrode.

3. In an electrical precipitator, electrodes as defined in claim 1 in which the extended surface member of the discharge electrode is positioned in the constricted zone provided by the projecting portions of the collecting electrode.

4. In an electrical precipitator, electrodes as defined in claim 2 in which the extended surface member of the discharge electrode is positioned in the constricted zone provided by the projecting portions of the collecting electrode.

ARCHIBALD F. MESTON.
